FURNACE ORGANIZATION

Perry C. Euchner, Jr., Ridgewood, N.J., assignor to Combustion Engineering, Inc., New York, N.Y., a corporation of Delaware

Filed July 23, 1957, Ser. No. 673,677

7 Claims. (Cl. 110—49)

This invention relates generally to furnaces wherein hot combustion gases are recirculated back to the furnace and has particular relation to an improved duct and system for reintroducing these gases into the furnace.

As is known in steam generating practice, superheated steam temperature may be controlled by gas recirculation. This gas recirculation is not required at all times. Therefore the duct that conveys the recirculated gases to the furnace does not have these gases passing through it at all times during operation of the steam generator. Since this duct leads directly into the furnace a serious problem exists with regard to maintaining a tight connection of the duct with the wall of the furnace and of preventing excessive thermal stresses from developing in this duct due to large temperature variations of the duct wall. This is so because when combustion gases are conveyed through the duct the duct wall will generally be at the same temperature as these gases while when these gases are not conveyed through the duct the end of the duct connected with the furnace may be heated to a very high temperature because of the intense heat in the furnace and due to possible eddy current of a small amount of hot furnace gases in the duct work adjacent to the furnace. While this problem is encountered with all types of firing it is particularly acute with a so-called pressure fired furnace wherein the pressure in the furnace is super-atmospheric and it is therefore essential that the furnace be absolutely tight.

It is an object of this invention to provide an improved gas recirculation organization and system for a furnace.

Other and further objects of the invention will become apparent to those skilled in the art as the description proceeds.

With the aforementioned objects in view, the invention comprises an arrangement, construction and combination of the elements of the inventive organization in such a manner as to attain the results desired as hereinafter more particularly set forth in the following detailed description of an illustrative embodiment, said embodiment being shown by the accompanying drawing wherein:

FIGURE 1 is a side view, somewhat diagrammatic and partially in section showing a steam generator within which is embodied the present invention;

FIGURE 2 is a top view of the gas recirculation duct arrangement and is taken generally from line 2—2 of FIGURE 1;

FIGURE 3 is a vertical sectional view taken along line 3—3 of FIGURE 2 and shows the detailed construction of the end of the duct connected with the furnace at an enlarged scale.

Referring now to the drawings, wherein like reference characters are used throughout to designate like elements, the illustrative and the preferred embodiment of the invention shown therein comprises a pressure fired furnace 10 which is provided with burners 12 that are effective to introduce fuel and air into the furnace where the fuel is burned. The walls of the furnace are lined with steam generating tubes 14 which are connected at their upper ends with the steam and water drum 16 and at their lower ends with header 18. Downcomers 20 extend downwardly from drum 16 and are also connected with header 18 with a circulation circuit thus being formed with the water flowing downwardly through

2

downcomers 20 and up through steam generating tubes 14. The combustion gases generated by burning fuel in furnace 10 pass upwardly through the furnace and through gas pass 22 with the gases then being reversely directed and flowing downwardly through gas pass 24 and out through main gas duct 26 which leads to air heater 28. Located within gas passes 22 and 24 are the high temperature superheater sections 30 and low temperature superheater sections 32, respectively, which are connected with the steam and water drum in a conventional manner to superheat the steam as desired. Also located in gas pass 24 is a conventional economizer 33.

Hot air for supporting combustion of fuel within furnace 10 is directed to burners 12 through duct 34 which extends from air heater 28 as shown.

As was previously mentioned, there is a tendency in a steam generator such as that illustrated in the drawing for the steam temperature, i.e., the superheat temperature leaving high temperature superheater 30, to drop with or as the load decreases on the steam generator. The generator is designed to produce its designed steam temperature at maximum load and therefore if no control means were provided the steam temperature would decrease as the load is decreased below this maximum value. However, it is generally essential that the steam temperature be maintained substantially constant over a wide load range and therefore control means must be provided to effect this result. This control may be achieved in a number of ways, and in the illustrative organization it is achieved by two well known means, one of which is by tilting burners 12 and the other by gas recirculation. The burners 12 are arranged generally in the corners of the steam generator so that the fuel and air is directed tangentially to a vertical cylinder in the furnace and are vertically tiltable so that the zone of combustion may be moved vertically within the furnace in a manner to maintain the steam temperature constant over a substantial load range. In addition to this control, gas recirculation is provided with gas recirculation duct 36 extending from main gas duct 26 and being connected to the lower end of the furnace for directing hot combustion gases thereto. Connected into the duct 36 is the recirculating fan 38 which is effective to force combustion gases into the furnace. With these two control

means control of the superheat temperature over a very wide load range may be had, as for example, with a 575,000 lbs. per hour steam generator, steam temperature control may be effected throughout a load range of 180,000 lbs. per hour to 575,000 lbs. per hour with tilting burners being effective to control the steam temperature throughout a load range of 300,000 lbs. per hour to 575,000 lbs. per hour and gas recirculating effecting the control through the range of 180,000 lbs. per hour to 300,000 lbs. per hour.

The gas recirculation control will not be required at all operating loads and in order to prevent the reverse flow of hot gases from the furnace through the gas recirculation duct dampers 40 and 42 are provided with damper 40 being immediately upstream of fan 38 and damper 42 being adjacent the inner end of the duct which is connected to the furnace with these dampers preventing flow through recirculation duct 36 when in their closed position. The inner end of this recirculation duct which is connected with the furnace must be joined to the furnace in a gas tight manner with this being particularly important in pressure fired units such as the one disclosed. The inner end of the duct is therefore welded to the steam generating tubes 14 that extend along the furnace walls with these tubes being suitably separated at the duct opening to permit the introduction of recirculated gases into the furnace through the duct and with

the connection of the duct with the furnace wall being gas tight.

In order to prevent the inner end of the duct from overheating during periods when combustion gases are not flowing through the duct and in order to prevent the duct wall from being subjected to severe temperature differentials as would occur from intermittent flow of combustion gases through the duct, the inner end of the duct is double walled as best indicated in FIG. 3 with there being an inner wall 44 spaced somewhat inwardly of outer wall 46 to provide a relatively narrow passage 48 entirely around the inner end of the duct and with spacers 50 maintaining these walls in properly spaced relation. The passage 48 extends from a location immediately upstream of dampers 42 to the extreme inner end of the duct that is connected with the furnace wall. Also provided in the inner end of the gas recirculation duct 36 are several directing vanes 52 which are also double walled as indicated in FIG. 2 providing a narrow passage, with these vanes also extending from a location immediately upstream of dampers 42 to the inner end of the duct 36. Hot air is directed to the duct 36 between dampers 40 and 42 when these dampers are in their closed position and for this purpose air duct 54 extends from duct 34 adjacent the outlet of air heater 28 into duct 36 at a location between these dampers with dampers 56 being provided in this air duct for controlling flow through it to gas recirculation duct 36. This air admitted to duct 36 through duct 54 is quite close to the temperature of the recirculated gases being somewhat lower in temperature than the recirculated gases since it is heated by these gases and this air flows through the narrow passage 48 formed by the double walls at the inner end of the gas recirculation duct and also through the passages formed by the double walled directing vanes 52 thereby keeping or maintaining the temperature of the duct and these vanes quite close to that which prevails when gas is being recirculated through the duct. It is a characteristic of these steam generators that the temperature of the air leaving the air heater and the temperature of the combustion gases directed through the air heater will be close to the saturation temperature of the generator which is the temperature of the steam generating tubes that line the furnace. This has the advantage of maintaining the duct wall which is connected to the furnace wall at generally the same temperature as the furnace wall so that the connection is not unduly stressed and accordingly will remain gas tight.

Thus with the present invention when recirculated combustion gases are not directed through the recirculation duct 36, as is the case at maximum load and may also be the case throughout a substantial portion of the upper load range when a control in addition to gas recirculation control is provided, hot air will be introduced into duct 36 by opening the damper 56 in air duct 54, which damper is of course closed when combustion gases are being recirculated. This introduction of hot air maintains the temperature of the inner end of the duct wall at generally the same temperature that the recirculation combustion gases would maintain it and also at generally the same temperature as the steam generating tubes that line the furnace wall and to which the duct is connected. Thus the inner end of the recirculation duct is not heated to the extremely high temperature to which it would otherwise be subjected during periods of no gas recirculation and accordingly overheating and overstressing of this inner end of the duct is eliminated.

While I have illustrated and described a preferred embodiment of my novel organization it is to be understood that such is merely illustrative and not restrictive and that variations and modifications may be made therein without departing from the spirit and scope of the invention. I therefore do not wish to be limited to the precise details set forth but desire to avail myself of such changes as fall within the purview of my invention.

What is claimed is:

1. In combination a furnace into which fuel is fired and burned, a duct connected to the furnace for introducing hot combustion gases thereinto said duct having its inlet connected to receive combustion gases generated in the furnace so as to reintroduce them back into the furnace, damper means in said duct adjacent the end connected to the furnace, said end of the duct connected with the furnace being double walled from a location immediately upstream of said damper means with the walls being spaced to provide a narrow passage, said passage leading from the duct interior upstream of said damper means into the furnace, with the damper means operating on the inner passage of the double walled duct only, and means for introducing a cooling gas into said duct upstream of said damper means when said combustion gases are not passing therethrough.
2. The organization of claim 1 wherein said end of the duct is provided with directing vanes that extend from a location immediately upstream of said dampers toward the duct extremity connected with the furnace and which are also double walled providing a narrow passage between said walls leading from said location into the furnace, with this passage being free of the damper means.
3. In combination a furnace into which fuel is fired and burned, a duct connected to the furnace for introducing hot combustion gases thereinto said duct having its inlet connected to receive combustion gases generated in the furnace so as to reintroduce them back into the furnace, damper means in said duct adjacent the end connected to the furnace, said end of the duct connected with the furnace being double walled from a location immediately upstream of said damper means with the walls being spaced to provide a narrow passage leading from the duct interior upstream of said damper means into the furnace, with the damper means operating on the inner passage of the double walled duct only, means for introducing hot combustion gases through the duct into the furnace, means operative to control such introduction, a source of hot air at a temperature generally corresponding with that of the combustion gas, and means for controllably introducing this air into said duct when the combustion gases are not introduced thereto.
4. In an organization of the type described the combination of a furnace having heat exchange tubes lining its walls, an airheater, duct means conveying combustion gases generated in said furnace to said air heater as the heating medium therefor, a recirculation duct connected at one end to said duct means and having its other end supported from the tubes lining the furnace wall with this other end being disposed so as to discharge combustion gases into the furnace, a fan in said recirculation duct for forcing the gases therethrough into the furnace, and adjustable damper means upstream of said fan and another adjustable damper means downstream of said fan in said recirculation duct with the latter damper means spaced somewhat from said other end of said recirculation duct, said other end of said recirculation duct being double walled from a location upstream of the second mentioned damper means with said double walls being spaced forming a narrow peripheral passage communicating at one end with the duct interior upstream of the second mentioned damper and with the furnace at the other end and with said other adjustable damper means operating on the inner passage of the double walled duct only, means for introducing hot air from the air heater into said recirculation duct intermediate said dampers, and adjustable means to control such introduction of air.
5. The organization of claim 4 including gas directing vanes in said other end of said recirculation duct extending from a location immediately upstream of the second mentioned damper generally to the end of the duct with said vanes being doubled walled and with double walls

being spaced to form a narrow passage open at both ends with this passage being free of the damper means.

6. In an organization of the type described the combination of a furnace in which fuel is burned, an air heater connected to receive the combustion gases generated in the furnace as the heating medium for the air heater, means for introducing a portion of the combustion gases leaving the furnace back into the furnace including a duct connected at one end to the furnace wall, means for controlling the flow of combustion gases through said duct including damper means in said duct spaced a short distance from said one end, means for controllably introducing air from said air heater into said duct upstream of said damper means, said one end of said duct from a location immediately upstream of said damper means to said one end of the duct having an outer wall and an inner wall complementary with the outer wall and maintained in spaced relation therewith so as to form a passage between the walls that communicate with the duct interior upstream of the damper means and with the furnace interior, and with the damper operating on the inner passage of the double walled duct only.

7. In combination a furnace in which fuel is burned, means for introducing a portion of the combustion gases exiting the furnace back into the furnace including a duct connected at one end to the furnace and a fan in said duct to force the gases back into the furnace, adjust-

able damper means intermediate said fan and the end of the duct connected with the furnace to prevent reverse flow of combustion gases through the duct when the recirculation of gases is not desired, the end of the duct connected with the furnace wall being double walled from a location immediately upstream of the damper means to the end connected with the furnace thereby forming a narrow annular passage about the inner passage of the duct with this annular passage leading from the duct interior upstream of the damper means to the furnace and with this narrow annular passage communicating with the furnace and the duct interior upstream of the damper means, the damper means operating on the inner passage of the double walled duct portion only and means for controllably supplying a heated gas between the fan and the damper means.
